ALFRED L. ATHERTON, OF PITTSBURGH, PENNSYLVANIA, ASSIGNOR TO WESTINGHOUSE ELECTRIC & MANUFACTURING COMPANY, A CORPORATION OF PENNSYLVANIA.

BALANCING MEANS FOR HOT-CATHODE RECTIFIERS.

Application filed November 20, 1920. Serial No. 425,486.

My invention relates to hot-cathode-rectifier systems and particularly to those systems employing a plurality of bulbs.

Full-wave, hot-cathode rectifiers are liable to cause noise if used on telephone batteries, the noise being due, at least in part, to differences in the bulbs. Differences in purity of gas, percentage of gas, filament temperatures, space between anode and filament and 5 filament area will make differences in the "bulb-potential-drops" or arc voltages across the bulbs, which result in noisy lines.

Variations in bulb-potential-drop may be effected by adjustment of the filament excitation, and I propose to use this means for neutralizing the variations in bulb-potential-drop which are due to other causes.

The single figure of the accompanying drawing is a diagrammatic view of apparatus and circuits embodying my invention. As here illustrated, my invention may consist 20 of a pair of bulbs 1 and 2, each having an anode 3 and a filamentary cathode 4. Power is supplied from any suitable alternating- 25 current source, such as the transformer windings 5, having a mid-point 6 which is connected to one terminal of the direct-current load, indicated as a battery 7, the other terminal of the direct-current load being connected to 30 the filament circuits.

The filaments are excited by means of a pair of auxiliary transformer coils 8. The coils 8 are connected in series, with their outer terminals connected, respectively, to corresponding terminals of the filaments 4. The other terminals of filaments 4 are connected together through an impedance means 9. A sliding contact member 10 cooperates with the impedance means 9 and is connected to 40 the common terminal of the coils 8, 8. The impedance means 9 may be a carbon pile or other resistance or it may be a reactance coil in the form of an auto-transformer, or any other suitable device.

With this arrangement, it is possible to 45 compensate for initial variations in the bulb-potential-drops, and also for changes in the bulb conditions after a long period of service, by adjusting the respective filament temperatures. Such adjustments may be made

satisfactorily by hand, since bulb conditions do not vary rapidly.

However, in case the requisite attendance is undesirable, automatic operation may be employed, as indicated schematically in the drawing, such means being shown as comprising coils 11 and 12, placed in series with the respective anode leads of the bulbs, and having armatures 13, 14 which are connected together by a rod 16 carrying the variable sliding contact member 10. The coils 11 and 55 12 are so arranged that an increase in current in either bulb circuit actuates the rod 16 and causes the sliding contact member 10 to decrease the filament-excitation current of 60 12. 65

It is to be understood, of course, that the automatic means shown is merely suggestive, as the details of such means do not constitute any part of my invention and any suitable 70 automatic means may be used.

I have shown my invention as applied to a single-phase circuit having two bulbs, one bulb rectifying each half wave of the alternating current. The compensating means which I have described is useful in maintaining the currents or voltages in successive half waves equal in value, thus obviating a particularly troublesome cause of noise in a telephone circuit 15 which may be connected to 75 the battery 7. 80

It is obvious, however, that my invention is not limited to telephone systems, but is applicable to a single rectifier or to a plurality of rectifiers arranged in parallel or arranged in a polyphase circuit. In fact, my filament-control means may be used to vary the load current of a rectifier bulb in any power circuit. It will be understood, therefore, that my claims will be construed to cover all modifications or equivalents which could be supplied by those skilled in the art. 85 90

I claim as my invention:—

1. The combination with an A. C. source, a plurality of hot-cathode half-wave rectifiers supplying a common load connected between said rectifiers and the neutral of said source, of automatic means for varying the cathode heating currents upon the occurrence of differences in the bulb-potential-drops. 95 100

2. The combination with a rectifier system comprising a plurality of filamentary bulbs supplying a common load, of means responsive to the respective anode currents of said bulbs for maintaining the currents in the several bulbs equal.

3. In a rectifying system, the combination with an A. C. source and a plurality of half-wave hot-cathode rectifiers each providing a space-current path from a line terminal of said source to a common load, a connection of the other terminal of said load to the neutral of said source, and automatic means for compensating for differences in potential-drops of the several rectifiers.

4. The combination with an alternating-current system and a direct-current system, of a pair of space-current devices operating in parallel across said direct-current system and operating on opposite half-waves of said alternating current system, means for adjusting the impedance of said devices, and means responsive to operating conditions in said devices for maintaining a predetermined relation between the impedances of the same.

5. The combination with a direct-current load, an alternating-current source, and a pair of rectifiers connected in parallel between said alternating-current source and said direct-current load to rectify opposite half waves of the alternating current, of means responsive to the difference in operating conditions in the two rectifiers for maintaining a predetermined relation in the operation of the two rectifiers.

6. The combination with a direct-current load, an alternating-current source, and a pair of rectifiers connected in parallel between said alternating-current source and said direct-current load to rectify opposite half waves of the alternating current, each of said rectifiers comprising a filamentary cathode, of means for exciting said filamentary cathodes, and means responsive to the difference in operating conditions in said two rectifiers for adjusting the relative degree of excitation of said two cathodes.

7. The combination with a direct-current load, a plurality of alternating-current sources, and a plurality of rectifiers connected in parallel between said direct-current load and said alternating-current sources, of means responsive to the operating conditions in said rectifiers for maintaining a predetermined relation between the impedances of the circuits of the several rectifiers.

8. In a space-current tube system, the combination with a plurality of space-current devices having separate hot cathodes, of energizing means for supplying heating current to said cathodes, and adjustable current controlling means connecting said energizing means to said cathodes, said controlling means being so arranged that an adjustment producing an increase of heating current in one de-

vice produces a decrease in the heating current in a second device.

9. In a space-current tube system, the combination with a pair of space-current devices having separate hot cathodes, of means for connecting said cathodes in series, and adjustable controlling means for supplying the heating current for said cathode through the series connection between the same, said controlling means being so arranged that an adjustment of the controlling means to produce a current increase in one cathode simultaneously produces a current decrease in the other cathode, and vice versa.

10. In a space-current tube system, the combination with two filamentary cathodes, of a source of electrical energy having two end terminals and an intermediate terminal, said cathodes being connected in series between said end terminals, and a conducting connection between said intermediate terminal and a point intermediate said cathodes.

11. In a space-current tube system, the combination with two serially connected filamentary cathodes, of a source of electrical energy having two end terminals connected in series with said two cathodes, said source having an intermediate adjustable terminal connection to an impedance intermediate said cathodes to control the current through the same, said adjustable terminal connection being so arranged that an adjustment producing a current increase in one cathode simultaneously produces a current decrease in the other cathode, and vice versa.

12. In a space-current tube system, the combination with two filamentary cathodes, of a source of electrical energy having two end terminals and an intermediate terminal, an impedance device connected between said two cathodes, the free terminals of said cathodes being connected to the end-terminals of said source, and a connection between said intermediate terminal and said impedance device.

13. In a space-current tube system, the combination with two filamentary cathodes, a source of electrical energy having two end terminals and an intermediate terminal, an impedance device connected between said two cathodes, the free terminals of said cathodes being connected to the end-terminals of said source, and means for connecting said intermediate terminal to various points on said impedance device to differentially control the current flowing through said cathodes.

14. In combination with a direct-current load, an alternating-current source, a pair of hot-cathode diode tubes connecting the respective line terminals of said source to the input terminal of said load, a connection from the other terminal of said load to the neutral of said source, and means responsive to differences in the load currents of said rectifiers to decrease the temperature of the cathode of the rectifier taking the larger load current.

15. In combination with a direct-current load, an alternating-current source, a pair of hot-cathode diode tubes connecting the line terminals of said source to the input terminal of said load, a connection from the other terminal of said load to the neutral of said source, and means responsive to differences in

the load currents of said rectifiers to increase the temperature of the cathode of the rectifier taking the smaller load current.

10

In testimony whereof, I have hereunto subscribed my name this 12th day of November 1920.

ALFRED L. ATHERTON.
